F. H. CALL.
OPERATING DEVICE FOR DISK INK ERASERS.
APPLICATION FILED JULY 17, 1918.

1,302,763.

Patented May 6, 1919.

FRANKLIN HALE CALL,
Inventor.

By C. C. Vrooman Esq.,
his Atty's.

UNITED STATES PATENT OFFICE.

FRANKLIN HALE CALL, OF PORTLAND, OREGON.

OPERATING DEVICE FOR DISK INK-ERASERS.

1,302,763.

Specification of Letters Patent.

Patented May 6, 1919.

Application filed July 17, 1918. Serial No. 245,349.

To all whom it may concern:

Be it known that I, FRANKLIN HALE CALL, a citizen of the United States, residing at Portland, in the county of Multnomah and

5 State of Oregon, have invented certain new and useful Improvements in Operating Devices for Disk Ink-Erasers, of which the following is a specification, reference being had therein to the accompanying drawings.

10 This invention relates to an operating device for disk ink erasers and has for its object the construction of a simple and efficient device that will collect the waste during the erasing process, and which device can be 15 accurately adjusted on the work when it is desired to make an erasure.

With this and other objects in view, this invention consists of certain novel combinations, constructions and arrangements of 20 parts, as will be hereinafter fully described and claimed.

In the drawings:

Figure 1 is a longitudinal sectional view of my device taken on line 1—1, Fig. 2, and 25 looking in the direction of the arrows.

Fig. 2 is a fragmentary top plan view of the device.

Fig. 3 is a view in front elevation of the front end of the device.

30 Fig. 4 is a transverse sectional view taken on line 4—4, Fig. 2, and looking in the direction of the arrows.

Fig. 5 is a horizontal sectional view taken on line 5—5, Fig. 1, and looking in the direction 35 of the arrows.

Fig. 6 is a rear view, in elevation, of the pivoted lever of the device.

Fig. 7 is a sectional view taken on line 40 7—7, Fig. 6, and looking in the direction of the arrows.

Referring to the drawings by numerals, 1 designates the handle of the device, which handle is provided with an integral forwardly-extending casing portion 2; the handle 1 also being hollow for receiving part 45 of the mechanism as well as the forwardly-extending portion 2.

Near the front end of the portion 2 I mount a thumb nut 3; by means of this ordinary fastening device I adjustably secure the rubber and waste-collector 4; the collector 4 is provided with an elongated slot 5 (Fig. 1) so as to allow of a sliding adjustment on the outer end of the handle-casing.

55 A resilient guard 6 is fastened at 7' to the front end of the collector 4, and in this guard

6 is an elongated slot or opening 7 through which the periphery of the rotary disk eraser 8 extends when the device is in operation for erasing something on a sheet. The guard 6 60 is placed free against the work and only that portion covered by the opening 7 of the guard will be erased. By reason of the resiliency of the guard 6 it prevents, to a great degree, injury of the device should the device be placed suddenly against the work; in other words the guard 6 acts in the capacity of a spring bumper for the entire device as the same is pressed against the work to be erased.

The disk eraser 8 (Fig. 4) is mounted upon the threaded sleeve 9, carried by the shaft 10. The shaft 10 is provided with a head 11 at one end, and upon the other end is mounted the pivoted spring latch 12, the latch 12 being pivoted at 13 upon the forwardly-extending portion 2 of the casing.

The latch 12 is engaged by the bowed spring 14 to keep the latch from being accidentally forced off one end of the shaft 10 80 (Figs. 2 and 4). The sleeve 9 is integral with a disk-portion 15 that is provided with penetrating spurs 16, and on the sleeve 9 is mounted a disk 17 that is provided with penetrating spurs 16, and a thumb nut 18 is 85 threaded upon sleeve 9 and clamped against disk 17 by causing the spurs 16 of disks 15 and 17 to enter the rubber eraser 8 and hold it against independent rotary movement upon the sleeve 9.

Integral with sleeve 9 is a sprocket wheel 19, and mounted upon the sprocket wheel is a ribbon belt 20, which belt 20 is provided with openings engaged by the sprocket of wheel 19, as well as by the dogs 21 and 22.

The primary dog 21 is pivoted at 23 upon the lever 24, and the auxiliary dog 22 is pivoted at 25 near the end of lever 24. The lever 24 is pivoted at 26 within the lower part of the handle-casing 1, and this lever is U-shaped in cross-section, as clearly seen in Figs. 6 and 7, which permits of spring 27 to be placed therein, at its outer end, after causing the lever 24 to normally move to its outer position, shown in Fig. 1. The spring 27 is coiled around pin 28, and as the spring 27 and its mounting is of an ordinary structure I am not specifically describing the details thereof; it is obvious that the spring 27 exerts an outward pressure or "push" upon lever 24 at all times.

The ribbon-belt 20 passes around wheel

29 mounted on shaft 30, and as lever 24 moves outwardly from the positions shown in dotted lines in Fig. 1, the auxiliary dog 22 will carry the belt 24 forwardly, and upon 5 the operator gripping the handle of the device and pressing inwardly on lever 24 the auxiliary dog 22 will rise out of the apertures in the belt 20, permitting the primary dog 21 to draw the lower run of the belt 10 backwardly and by the continuous alternating action of the two dogs when the device is in operation, continuous rotary movement will be imparted to the rotary disk eraser 8.

By slightly swinging the latch outwardly 15 to clear the end of the shaft 10 and then raising the latch vertically as shown in Fig. 1, and then unscrewing the nut 18, a new eraser 8 can be quickly placed upon the device. Further, by adjusting the collector 4 20 the guard 6 can be adjusted to provide for any wear occurring upon the disk 8, and in this manner the disk can be entirely used, since the collector for the trash caused by the erasing action and the resilient guard 25 carried thereon can accommodate any other adjustment to the wear on the rotary eraser 8.

The speed of the rotary eraser 8 depends upon the rapidity with which the lever 24 is drawn inwardly, since the spring 27 is 30 strong enough to quickly return the lever 24 to its outer position; all that is needed is for the operator to draw inwardly on lever 24 and quickly release it, which will result in the rotary eraser being driven rapidly 35 through the action of said lever 24, dogs 21 and 22 and belt 20.

The collector 4 is provided with horizontal flanges 4^a (Fig. 3) that fit in flanged portions 2^a formed on the lower portion of the 40 outer end of the forwardly-extending portion 2 of the handle casing. These flanges 4^a of the collector 4 support the collector upon the primary casing and the fastening device 3, together with slot 5, allows the 45 adjustment of the collector 4, as hereinbefore described.

What I claim is:

1. In a device of the class described, the combination, with a primary casing, a rotary eraser mounted on the forward end thereof, of a collector provided with a resilient guard, adjustably mounted upon said casing contiguous to said eraser and manually operated means in said casing and co-operating with said eraser for rotating the same.

2. In a device of the class described, the combination with a casing, of a rotary eraser mounted upon said casing, and a lever and belt means carried by said casing and co-operating with said eraser for rotating the same.

3. In a device of the class described, the combination with a casing, of rotary eraser means carried by said casing, a ribbon belt 65 in said casing and co-operating with said eraser means for rotating the same, a spring-pressed lever carried by said casing and positioned contiguous to said belt, and a plurality of dogs carried by said lever and engaging said belt for driving the belt for imparting rotary motion to the eraser means.

4. In a device of the class described, the combination of a casing provided with inwardly-extending flanges at its forward end, 75 a dust collector provided with outwardly-extending flanges mounted in the inwardly-extending flanges of the casing, a resilient guard provided with an eraser receiving opening secured near its lower end to said 80 collector, means on the casing and collector for securing the collector upon the casing, a rotary eraser carried by the casing and extending into the collector, and being adapted to project slightly through the 85 eraser opening of the guard, and means carried by the casing and eraser for manually rotating the eraser.

5. In a device of the class described, the combination with a casing, of an axle having one end secured on the casing, a pivoted latch carried by the casing and detachably supporting the other end of said axle, an eraser, means on the axle for detachably clamping said eraser on said axle, and means 95 carried by the casing and co-operating with the clamping means of the eraser for rotating said eraser.

6. In a device of the class described, the combination with a casing, of a lever U-shaped in cross-section, pivotally mounted at its lower end within the casing, a spring carried by the casing and extending into the U portion of the lever, removable eraser means carried by the casing, and means co-operating with the eraser means and with the lever for imparting movement to the eraser means when the lever is moved upon its pivot.

In testimony whereof I hereunto affix my 110 signature.

FRANKLIN HALE CALL.
